CLAIM

We claim the ornamental design for a probe supporter for ultrasound diagnostic apparatus, as shown and described.

DESCRIPTION

FIG. 1 is a front perspective view of a probe supporter for ultrasound diagnostic apparatus showing our new design;
FIG. 2 is a front view thereof;
FIG. 3 is a rear view thereof;
FIG. 4 is a left-side view thereof;
FIG. 5 is a right-side view thereof;
FIG. 6 is a top view thereof;
FIG. 7 is a bottom view thereof;
FIG. 8 is a rear perspective view thereof; and,
FIG. 9 is another rear perspective view thereof in condition of use.

The broken lines depicting an ultrasound diagnostic apparatus in FIG. 9 represent an environment, and the remaining broken lines illustrate portions of the probe supporter for the ultrasound diagnostic apparatus that form no part of the claimed design.
